ATTORNEY

UNITED STATES PATENT OFFICE.

CLYDE BRYAN, OF SALEM, OHIO.

WINDOW CURTAIN AND SHADE ADJUSTER.

SPECIFICATION forming part of Letters Patent No. 766,589, dated August 2, 1904.

Application filed May 11, 1904. Serial No. 207,362. (No model.)

To all whom it may concern:

Be it known that I, CLYDE BRYAN, a citizen of the United States, residing at Salem, in the county of Columbiana and State of Ohio, have 5 invented certain new and useful Improvements in Window Curtain and Shade Adjusters; and I do hereby declare that the following is a full, clear, and exact description of the same, reference being had to the annexed drawings, 10 making a part of this specification, and to the numerals of reference marked thereon, in which—

Figure 1 is a side elevation of a window-frame, showing the different parts of my improved window curtain and shade adjuster properly connected and illustrating a shade and curtain placed in position. Fig. 2 is view of one of the guide-tubes, showing said tube partly in section and illustrating the shade and 20 curtain holding rod located therein, also showing the position of the clamping-knob. Fig. 3 is a transverse section taken on line C C, Fig. 2, except that in Fig. 2 the tube is shown in section, while in Fig. 3 the tube is shown full. 25 Fig. 4 is a view of one of the guide-tube-holding sockets, showing a portion of the window-frame. Fig. 5 is a transverse section of the guide-tube and curtain and shade holding rod, showing the position of the clamping-knob. 30 Fig. 6 is a view showing a portion of the shade and curtain holding rods and illustrating one of the curtain-brackets fixed thereto.

The present invention has relation to window curtain and shade adjusters; and it consists in 35 the novel arrangement hereinafter described, and particularly pointed out in the claim.

Similar numerals of reference indicate corresponding parts in all the figures of the drawings.

40 In the accompanying drawings, 1 represents the guide-tubes, which are secured to the window-frame 2 and located substantially as shown in Fig. 1.

The tubes 1 are supported by means of the 45 sockets 3, which sockets are secured to the window-frame 2 and into which sockets the bottom or lower ends of the guide-tubes 1 are seated, substantially as illustrated in Figs. 1 and 2.

The top or upper ends of the guide-tubes 1 50 are held in proper position by means of the screw-eyes 4, which screw-eyes are provided with the inturned flanges 5, which flanges fit in the open slots 6, formed in the guide-tubes 1.

It will be understood that the guide-tubes 1 55 should be held so that they cannot rock or turn, and in order to accomplish this result the sockets 3 are provided with the set-screws 7 and the flanges 5, seated in the slots 6, thereby preventing any twisting or turning of the 60 guide-tubes.

Within the guide-tubes 1 are located the shade and curtain holding rods 8, which rods are adapted to move up and down in the guide-tubes 1. To the rods 8 are attached the curtain-pole-holding brackets 9 and the shade-holding brackets 10 and 11, said brackets being of the usual construction used in supporting shade-rollers known as "spring-rollers."

For the purpose of holding the rods 8 at any 70 desired point of adjustment each of the rods are provided with the screw-threaded shank 12 and upon which screw-threaded shank is located the knob 13, and between the guide-tubes 1 and the inner ends of the knobs 13 are 75 located the binding-plates 14.

It will be understood that when the knobs 13 are turned in one direction they will release the rods 8, at which time they are free to be moved up and down in the guide-tubes, 80 thereby adjusting the curtain-pole bracket and shade-roller brackets to any desired point, and when said parts have been brought into proper adjustment the knobs 13 are turned in the direction to clamp the rods 8 and hold 85 them at the desired point of adjustment.

It will be understood that by providing the screw-eyes 4 with the inturned flanges 5 said eyes can be adjusted up and down, or, in other words, can be attached at the most convenient 90 point or points of the window-frame proper, owing to the fact that the inturned flanges 5 can be moved up and down through the slots 6, or the tubes 1 can be moved upward after the screw-eyes have been properly attached and 95 the bottom or lower ends of the tubes seated in their sockets.

Having fully described my invention, what

I claim as new, and desire to secure by Letters Patent, is—

The combination of guide-tubes provided with slots, screw-eyes provided with inturned flanges, said flanges being adapted to be located in the slots of the tubes, curtain and shade roller brackets secured to rods, said rods located in the guide-tubes and sockets adapted to support the guide-tubes, and means for holding the curtain and shade bracket rods in

proper adjustment, substantially as and for the purpose specified.

In testimony that I claim the above I have hereunto subscribed my name in the presence of two witnesses.

CLYDE BRYAN.
